Gray, Elmes
ATTORNEY

UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

PHOTORADIOSCOPE

Application filed January 9, 1928, Serial No. 245,349. Renewed April 5, 1930.

My invention relates to the reproduction of pictures and the like transmitted from a remote point by radio or wire, and particularly to the method and apparatus for displaying the pictures as produced.

5 An object of my invention is to provide an arrangement for displaying radio or wire pictures as they are produced and particularly adapted to enable an onlooker to continuously watch a picture received over radio or wire transmitting and receiving systems as it is being developed or reproduced.

Another object of my invention is to provide an arrangement useful for advertising purposes for displaying pictures as produced 15 in accordance with radio or wire impulses actuating a reproducer for rebuilding the picture or facsimile at a remote point from the transmitter.

20 Another object of my invention is to provide a "photoradioscope" in the form of a display rack for pictures in which the picture recording surface is advanced with respect to a recorder in accordance with the 25 rate of building up the picture.

Other objects of my invention are to produce in a manner hereinafter set forth a "photoradioscope" which is simple in its construction and arrangement, durable, compact, 30 efficient, conveniently operated, readily set up, and inexpensive to install, as well as other objects which will be apparent from a reading of the specification when considered together with the accompanying drawings 35 which form a part of my specification.

My invention in one of its preferred forms is illustrated by the accompanying drawings, wherein;

Fig. 1 is an assembly drawing of one embodiment of the photoradioscope in accordance with my invention; and,

Fig. 2 is a detail view of a part of Fig. 1 showing one form of advancing mechanism for moving the recording surface with respect to the recording means.

To now make reference to the accompanying drawings, the same comprises a picture reproducing machine and a display rack which I have termed a "photoradioscope" 45 attached thereto, although it is within the

scope of the invention to arrange the display apparatus entirely separate from the reproducing machine. A paper of a suitable character for recording the picture impulses as received is passed through the photoradioscope and is periodically advanced with respect to a recording means, so that an audience looking at the arrangement may follow the progress of building up the picture in its separate line for line passages, so as to finally form a finished picture.

For originally transmitting the pictures an arrangement of any known description may be used, although I prefer to utilize arrangements of the general character disclosed by my copending application, Serial Numbers 695,175; 726,235; and 101,611, filed February 26th, 1924; July 16th, 1924; and April 13th, 1926, respectively. Synchronizers of any desired types may be used for coordinating the speeds of the moving elements at the transmitter and receiver.

The picture reproducing arrangement may, if desired, be of a similar nature to that which has been disclosed in my copending application, Serial Number 128,720, filed August 12th, 1926, in which a heat sensitive paper was mounted upon a drum or cylinder across which a heated air jet was passed, and in which the heat was periodically dissipated by the action of a cold air jet governed in accordance with received signal impulses, which were proportional to the various color intensities of the picture being transmitted.

In accordance with a preferred embodiment of my invention, such as has been illustrated for the purpose of showing a concrete example of the present machine, I have chosen to reciprocate a carriage 1, which may be of the character disclosed in the above referred to copending application, Serial No. 128,720, by means of a rotating shaft 3 which I have termed "a cam shaft". The shaft 3 is provided with an endless reversed spiral cam slot 5 cut therein and a pin (not shown) 90 extending downwardly from the carriage 1 is arranged to slide therein to produce a motion or travel of the carriage 1 back and forth longitudinally of the rotary shaft 3.

The carriage 1 preferably includes a pair 100

of air jets 7 and 9 which I will hereinafter term "hot air jet" 7 and "cold air jet" 9. Air from an external source (not shown) is directed to the air jets 7 and 9 through a tube 11. The air jet 7 is provided with a heating coil 13 which warms the air passing through the jet at all times. The air from the hot air jet 7 is projected outwardly through a nozzle 15 toward a cylinder 19 carrying a recording medium 21 which is preferably of the character sensitive to the application of heat so that it may be influenced by the hot air from jet 7 bearing the nozzle 15. The air in the jet 9 is directed from a nozzle 17 in a direction which crosses the path of the hot air issuing from nozzle 15 and dissipates the same in accordance with received signal impulses which control through electromagnetic means (not shown) the cold air passing through the jet 9, as has been disclosed by my copending application Serial No. 128,720, and also by my copending application Serial No. 245,350, filed Jan. 9, 1929.

25 The rotary cam shaft 3 and the cylinder 19 for carrying the recording surface 21 are supported at their ends in any desired manner by means of end supports 23 and 25, and carried by the end support 25 in any desired 30 manner in an appropriate form of gear train (not shown) for driving the cam shaft 3 at any predetermined and desirable speed from a motor (not shown). Directly beneath the cam shaft 3 is a long spindle 27, also carried 35 at its ends by the supports 23 and 25, for guiding the carriage 1 in its longitudinal motion on the cam shaft 3 by means of pins 29 extending downwardly from the carriage 1 and arranged to ride on either side of the 40 spindle 27. The pins 29 prevent the carriage from turning as the shaft 3 is rotated and cause the carriage to assume the above referred to longitudinal motion back and forth in both left to right and right to left 45 directions of the cam shaft 3.

Carried by the end supports 23 and 25 are upright support members 31 and 33 which extend for a considerable distance above the carriage 1 and cylinder 19. These upright 50 supports 31 and 33 are braced in any desired manner by suitable cross braces and angular braces attached as shown by the drawings. At the upper ends of the uprights 31 and 33 is a roller 35 over which the 55 recording medium 21 is arranged to pass after being advanced, in a manner to be hereinafter described, from the recording cylinder 19. For the purpose of tightly holding the recording surface on the roller 35 a 60 small clamping roller 37 is also provided and held by means of a clamp 39 tightly against the roller 35. Associated with the cylinder 19 and arranged similarly to the clamp roller 37 with respect to the roller 35 is a roller 65 41 arranged tightly against the cylinder 19

and providing a tight drive for the paper or recording medium 21.

To now make reference to the means for advancing the recording surface 21 with respect to the cylinder 19 at the end of each longitudinal motion of the carriage 1 carrying the air jets 7 and 9 along the cam shaft 3 I have provided a clutch mechanism, generally designated 43.

The clutch portion 43 is formed of two halves 45 and 47 which are forced together by means of a spring 49 carried about a threaded spindle 51 supported from the end support 23 of the frame. The tension of the spring 49 bearing against the clutch portion 47 is adjusted by means of an adjustable nut 53 carried by the threaded spindle 51. The portion 45 of the clutch, generally designated 43, has one or more pins 55 carried on its periphery, for a purpose to be hereinafter set forth.

Also, formed as a part of the clutch portion 45 is a worm wheel 57 for the purpose of driving a large pinion 59 which operates through any preferred form of gear mechanism, generally designated 61, to turn the cylinder 19 at predetermined time intervals by a rotation of the worm 57. The other end 63 of the worm 57 is formed similarly to the clutch portion 45 except that it has no pins 95 extending from the periphery thereof. This portion 63 rests upon and rotates through frictional engagement a large collar 65 which is carried securely on a spindle 67 which extends through the inside of the worm 57, the clutch portions 45 and 47, and the threaded spindle 51 and is securely fastened to the threaded spindle 51 in a collar or internally threaded nut 69. The spindle 67 is rotating at all times and derives its motion from a gear mechanism, generally designated 71, which is turned by any desired prime mover (not shown) and is, therefore, at all times rotating the threaded spindle 51 and the clutch portion 47 rigidly fastened thereto by any 100 preferred form of clamping mechanism such as a set screw. It is thus seen that from motion derived through the turning of the spindle 67 the clutch portion 47 will tend to 105 turn the portion 45 and thus rotate the worm 57 and its associated pinion 59 and gear mechanism 61 by means of a friction drive such as is derived from the pressure of the spring 59 upon the clutch portion 47 if no means is provided for preventing this frictional drive 110 and, therefore, the recording surface or medium 21 would be advanced at all times through a rotation of the cylinder 19 forming a frictional drive with the clamping roller 41. I have, therefore, provided means for interrupting this motion so that the motion of the recording surface may only take place at 115 periods when the carriage 1 carrying the air jets 7 and 9 has reached each end of its longitudinal motion with respect to the cam shaft 120

125

130

135

3 and this briefly includes a trip mechanism, generally designated 73.

The trip mechanism includes a spindle 75 extending longitudinally of the rotary cam shaft 3 and the cylinder 19 and supported by the end supports 23 and 25. About the spindle 75 a U-shaped projection on the carriage 1 is arranged to slide freely. At either end of the spindle 75 I have arranged and rigidly fixed collars 77 which, due to the engagement of the U-shaped projections, move the spindle 75 in one direction or the other as the carriage 1 reaches one or the other end of its longitudinal motion on the rotary cam shaft 3. The end of the spindle 73 is formed in a recessed or opposed V construction 79 and in this portion a roller 81 carried by the trip mechanism 73 is adapted to rest. As the spindle 75 is moved in one or the other direction the roller will be moved to the left (looking at Fig. 2) by reason of the fact that it is starting at the center of the opposed V-shaped grooves in the spindle 75 and moved to ride on the spreading portion of the V as the spindle is moved in one or the other direction. The yoke 83 is pivotally mounted through the end support 23 and at its end toward the cylinder 19 a spring 85 is provided for holding the yoke 83 in a position toward the spindle 75 so that the roller 81 which is carried by the yoke 83 will be in engagement with the V portion of the said spindle 75. Mounted on supports 87 and 89 on the yoke 83 are two extending pins 91 and 93 upon which the pins 55 extending outwardly from the periphery of the clutch portion 45 are adapted to catch and thus prevent rotation of the clutch portion 45, even though the portion 47 is tending by the frictional drive to rotate the same. As the spindle 75 moves in and out due to a motion of the carriage 1 back and forth longitudinally of the rotary cam shaft 3, the roller 87 will move the trip mechanism 73 to the left against the action of the spring and the pin 55 will be released from the extending pin 91 carried by the support 87 of the yoke 83 so as to permit the clutch portion 45 to rotate freely with the clutch portion 47 until the pin 55 has turned sufficiently to come in contact with the extending pin 93 carried by the yoke 83, which in the case of only a single pin on the clutch portion 45, will be a complete turn, and for more pins a proportionate amount, and then as the roller 81 again moves to the center of the V-shaped recess on the spindle 75 the pin 55 will slip from the extending pin 93 and come against the pin 91. As the motion of the spindle 75 is repeated the pin will slip and again permit the turn 47 of the clutch to drive the portion 45. It is readily seen that, as this happens at each stroke of the carriage 1, the worm 57 will be turned a certain amount and consequently the cylinder 19 prop-

tionately rotated so as to advance the recording surface 21 with respect thereto.

Also, driven from the gear mechanism 61 is an upright spindle 95 which is at all times turning similarly to the spindle 67 extending through the clutch 43. This spindle 95 drives a shaft 97 through any appropriate type of universal joint 99 and the shaft or spindle 97 extends upwardly along the upright support 31 to the top portion thereof where a second universal joint 101 drives a short spindle 103 to rotate a clutch 105 in a manner similar to that described in connection with the rotation of clutch 43 except that no trip mechanism is provided for the clutch 105. The clutch 105 has a spring 107 tending to turn both parts of the same and rotate through a worm and gear mechanism 109 the upper roller 35. However, when the recording surface 21 is held with respect to the cylinder 19 by the action of the pins 55 on the clutch 43 the recording surface can not be moved with respect to the roller 35 and, therefore, the clutch 105 merely slips and can not pull the recording surface upward, but as soon as the pins 55 are released to permit a rotation of the cylinder 19 and its associated roller 41, the clutch 105 will turn the roller 35 and move the paper 21 upward and at the same time keep the paper tight with respect to the upright, so that as a picture formed by the action of the air jets 7 and 9 on the recording surface, the latter may be periodically advanced upwardly from the recording cylinder 19 toward the top of the photoradioscope and enable an audience viewing the same to continuously watch the progress of reproducing the picture as received by any appropriate type of radio or wire receiver actuating the signal recorders in the form of the air jets 7 and 9. It is convenient to provide recording medium or heat sensitive paper on a roll and I have, therefore, provided on the end supports 23 and 25 of the recording machine, a rack or support spindle 111 to carry the recording paper. From the support spindle 111 the paper is led from the roll under the cylinder 19 and between it and the roller 41 and thence upwardly to be passed between the roller 35 and its associated clamping roller 37.

In many cases it has been found desirable to provide a means for illuminating the picture as it is being developed, especially, in cases where the apparatus is displayed in store windows and can be conveniently used for advertising purposes at night and I have, therefore, provided on the sides of the upright portion of the frame work 31 and 33 lights 113 mounted in front of reflectors 115 for the purpose of directing light rays across the recording surface 21.

It is, therefore, clear that my invention provides a means for displaying pictures

which are produced according to the present disclosure in line by line formation by the action of a recording jet upon a sensitive recording medium and advancing the picture 5 as it is produced in its line by line formation a predetermined distance at interrupted intervals in accordance with the time for marking a single line of the picture, the advance distance being equal to the width of one line 10 of recording which forms an excellent means for displaying the picture as produced for the purpose of advertising, explaining the process to others, and demonstrating the utility of the recording apparatus as well as 15 for many other uses.

While I have confined my description as relating to the radio or wire transmission and reproduction of pictures it is to be distinctly understood that the term "picture" 20 applies to the transmission and reproduction of manuscripts, finger prints, newspaper clippings or pages, blue prints, checks, diagrams of all descriptions, as well as other forms of printed matter and such things as 25 are adapted to make a visible impression on the eye and I, therefore, believe that my invention should only be limited in its scope so far as the limitations expressed throughout the various appended claims necessitate.

30 Having described my invention I am entitled to all modifications such as fall fairly within its spirit and scope as defined by the following claims wherein;

I claim:

35 1. A photoradioscope, including, a picture recording machine, a frame work associated therewith, a recording surface carried by said frame work and said recording machine, means for producing marks on said recording machine in accordance with received signal impulses, means for periodically advancing the recording surface with respect to said marking means, and means for providing an interrupted motion of said advancing 40 means for said recording surface in accordance with the rate of reproduction of a single line of a received picture irrespective of the direction of said reproduction.

2. A photoradioscope for displaying pictures, which includes, a picture recording machine and associated signal actuated recording means, a frame work carried by said recording machine, a roller on said frame work and said recording machine, a recording surface carried by each of said rollers, means for advancing said recording surface with respect to said rollers and said signal actuated recording means, and means for producing an interrupted motion to said advancing means for advancing the recording surface a single step for each movement of the signal actuated recording means across the recording surface irrespective of direction of said movement.

65 3. A photoradioscope, including, a pic-

ture recording machine and associated signal actuated recording means, a frame work carried by said machine, a roller upon the said machine and the upper portion of said frame work, a recording surface carried by each of said rollers, means for moving said signal actuated recording mechanism back and forth transversely of said recording surface, and means for interruptedly advancing the said recording surface a predetermined amount at the end of each transverse motion of the signal actuated recording mechanism irrespective of the direction of said movement.

4. A photoradioscope for displaying electrically transmitted pictures at a point remote from a transmitter, which includes, a picture recording machine and associated signal responsive recording means, a frame work supported by and extending above said machine, a substantially flat recording surface for recording pictures, said surface being carried by said machine and the upper portion of said frame work, and means for advancing said recording surface in step by step movements upwardly of said recording machine to the upper portion of said frame work and away from said recording means, whereby the picture as received may be produced so as to be at all times visible during its reproduction.

5. The method of displaying pictures received from a distant point, which comprises, recording impulses varying in intensities in accordance with received signal strength, producing a visible record from said signals, displaying said visible record of the said marking impulses, and advancing the said visible record periodically and interruptedly in accordance with the rate of marking a single line of the received picture irrespective of the direction of said marking.

6. A photoradioscope for displaying transmitted pictures, which includes, a picture recording machine and associated signal actuated recording means, a frame work carried by said machine, rollers on said frame work and said machine, a recording surface carried by said rollers, means for moving said signal actuated recording means back and forth transversely of said recording surface, means associated with one of said rollers tending to continuously advance said recording surface, and means associated with the other of said rollers on said machine for interrupting the advance of said recording surface and permitting the said surface to be advanced a predetermined amount at the end of each transverse stroke of said recording means, whereby a new line of marking impulses is produced on said recording surface.

7. A photoradioscope for displaying received pictures, which includes, a picture recording machine and an associated signal actuated picture recording means, a picture

- displaying frame work supported by said machine, a set of rollers on said frame work and upon said machine, a recording surface carried by each of said sets of rollers, means 5 for moving said signal actuated recording means back and forth transversely of said recording surface, friction drive means associated with one of said rollers tending to continuously advance the said recording surface 10 with respect to said rollers, and means associated with the other of said rollers on said machine for interrupting the advance of said recording surface during each transverse movement of said recording surface 15 and permitting the said surface to be advanced a predetermined amount at the end of each transverse stroke of said recording means irrespective of the direction of said stroke, whereby a new line of marking 20 pulses is produced on said recording surface for each longitudinal movement of said recording means. 8. A photoradioscope for displaying electrically transmitted pictures which includes 25 a signal actuated recording mechanism, a display means for the reproduced pictures associated with said recording mechanism, a recording surface carried by said display means and subject to the influence of said recording mechanism, and means for producing a relative motion between said recording mechanism and said recording surface for continually presenting portions of the recording surface uninfluenced by received 30 signals to the action of said recording mechanism for each change in the path thereof with respect to the said surface and irrespective of the direction thereof. 9. A photoradioscope including a picture 35 recording machine and associated signal actuated recording means, a frame work carried by said machine, a roller upon the said machine and the upper portion of said frame work, a recording surface carried by each of 40 said rollers, means for moving said signal actuated recording mechanism back and forth transversely of said recording surface, and means for advancing the said recording surface by predetermined amounts for exposing uninfluenced sections of the surface to 45 recording action upon each transverse movement of the signal actuated recording mechanism irrespective of the direction of movement thereof. 50 10. A photoradioscope for displaying transmitted pictures which includes a picture recording machine and associated signal actuated recording means, a frame work carried by said machine, rollers on 55 said frame work and said machine, a recording surface carried by said rollers, means for moving said signal actuated recording means back and forth transversely of said recording surface, means associated with one 60 of said rollers tending to continuously ad- 65 vance said recording surface, and means associated with the other of said rollers on said machine for controlling the advance of said recording surface and permitting the said surface to be advanced a predetermined amount for a transverse stroke of said recording means in each direction, so as to continually present a portion of said surface uninfluenced by signals to the action of said recording means. 70 75 RICHARD HOWLAND RANGER. 80 85 90 95 100 105 110 115 120 125 130

CERTIFICATE OF CORRECTION.

Patent No. 1,819,197.

Granted August 18, 1931, to

RICHARD HOWLAND RANGER.

It is hereby certified that error appears in the printed specification of the above numbered patent requiring correction as follows: Page 4, line 61, claim 2, before the word "movement" insert the word transverse; and that the said Letters Patent should be read with this correction therein that the same may conform to the record of the case in the Patent Office.

Signed and sealed this 17th day of May, A. D. 1932.
